US00D569806S

(12) **United States Design Patent** (10) Patent No.: **US D569,806 S**
(45) Date of Patent: **** May 27, 2008**

(54) **ELECTRICAL CONNECTOR**

(75) Inventors: **Qi-Sheng Zheng**, Kunshan (CN);
Zhong-Hua Yao, Kunshan (CN);
Xiao-Min An, Kunshan (CN)

(73) Assignee: **Hon Hai Precision Ind. Co., Ltd.**,
Taipei Hsien (TW)

(**) Term: **14 Years**

(21) Appl. No.: **29/288,895**

(22) Filed: **Jun. 26, 2007**

(51) LOC (8) Cl. **13-03**

(52) U.S. Cl. **D13/147**

(58) Field of Classification Search **D13/133, D13/146-147, 154, 184, 199; 439/63, 78, 439/108, 540.1, 541.5, 607-610, 620.06, 439/620.15, 620.21, 638, 676**

See application file for complete search history.

(57) **CLAIM**

The ornamental design for an electrical connector, as shown and described.

DESCRIPTION

FIG. 1 is a front, top and right side perspective view of an electrical connector showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines shown in the drawings are for illustrative purposes only and form no part of the claimed design. The bottom plan view of the electrical connector forms no part of the claimed design and has been omitted.
